BELT LINK FOR CARTRIDGES

Leo A. Carten, Washington, D. C.

Application March 13, 1942, Serial No. 434,513

3 Claims. (Cl. 89—35)

(Granted under the act of March 3, 1883, as
amended April 30, 1928; 370 O. G. 757)

The invention described herein may be manufactured and used by or for the Government for governmental purposes, without the payment to me of any royalty thereon.

This invention relates to a cartridge feed belt of the disintegrating type and more particularly to an improved link for such a belt.

In the use of automatic guns in aircraft and similar military applications it is essential that the greatest possible length of ammunition belt 10 be immediately available in a suitable box or magazine.

It is therefore the primary object of this invention to produce a belt link having enough strength to allow the full belt lifting capacity of 15 the gun feed mechanism and/or any auxiliary feed mechanism to be completely utilized.

It is a further object to produce a belt link which will have symmetrical feeding characteristics when fed from right or left and with either single or double loop leading.

An additional object is to produce a belt link which may be economically and conveniently manufactured.

The exact nature of the invention as well as other objects and advantages thereof will clearly appear from a description of a preferred embodiment as shown in the accompanying drawings in which:

Figure 1 is a perspective view of the new link.

Figure 2 is a top plan view of the new link.

Figure 3 is an end elevational view of the new link.

Figure 4 is a sectional view on the line 4—4 of Fig. 2.

Figure 5 is a plan view of the blank from which the link is fabricated.

Figures 6 and 7 are plan views of a belt assembled with the new links, Figure 6 showing the single loop leading and Figure 7 showing the double loop leading.

Figures 8 and 9 are perspective views showing a belt assembled from the old links, Figure 8 showing the single loop leading and Figure 9 showing the double loop leading.

Figure 10 is an end elevational view of the old link.

Belts of this type are usually made up of a plurality of individual links each comprising a pair of spaced apart but axially aligned cartridge gripping loops and a single connecting loop extending laterally from the link body and adapted to be received between and in axial alignment with the spaced loops of an adjacent link. In such belts the cartridges inserted through the

loops form the pintles in a flexible belt which disintegrates as the cartridges are fed into the receiver of the gun and successively withdrawn by the extractor mechanism.

In belts of this character commonly used heretofore and shown in Figs. 8, 9 and 10 the individual links 1 have been formed in the cross sectional shape of a letter W, the arms of the W having been closed upwardly upon the central point 2 to form the connecting loop 3 and the cartridge engaging loops 4 and 5 as best shown in Fig. 10. This type of link comprises a longitudinal body portion 6 having a laterally offset central section. From the lower edge of this central section the connection loop 3 extends downwardly and is turned upwardly and closed upon the upper edge of the body portion which forms the central point 2 of the W. From the upper edge of the end portions of the body 6 the coaxial spaced loops 4 and 5 extend downwardly and are turned upwardly and closed upon the upper edge 2 to form cartridge gripping loops. It will be obvious that when links of this character have been assembled into a belt and are fed into a standard Browning machine gun from the left, double loop leading as shown in Fig. 9, the feed pawl 7 shown in dotted lines will engage the links in a position in which there will be but a single thickness of metal between the feed pawl 7 and the cartridge body 8. When the same belt is fed from the same side, single loop leading as shown in Fig. 8, the feed pawl 7 will engage the body portion 6 of the link which overlies the spaced loops 4 and 5 and there will be a double thickness of metal between pawl 7 and cartridge body 8. In actual practice this lack of symmetry has resulted in malfunctions to such an extent that army practices require the double loop to be leading, whether the feeding is from the right or left side of the gun. The disadvantageous conditions introduced by the said lack of symmetry are overcome by links made in accordance with the present invention.

A similarly unsymmetrical condition will prevail with respect to engagement with the holding pawl when the belt is fed to the gun from the right with either single or double loops leading.

The new link shown in Figures 1 to 7 comprises a body portion 9 from the lower end edges of which extend a cartridge neck engaging loop 10 and a cartridge body engaging loop 11, the loops 10 and 11 being coaxial and longitudinally spaced from each other. It will be noted that the body portion 9 includes a pair of spaced apart

wall portions 9a and 9b. The loop 10 is formed on the wall portion 9a as an extension thereof which curves into a circle terminating at a free edge 10a of the wall portion 9a. The loop 11 curves similarly as an extension of the wall portion 9b and has its terminal end portion lying in close proximity to a free edge 11a on the wall portion 9b. From the central upper edge of the body portion 9 a connecting loop 12 extends in an opposite direction from the loops 10 and 11. The intermediate part of the body portion or section, herein designated by the numeral 9c, provides for the formation of the connecting loop 12. The body portion 9c has a free edge 12a toward which the terminal end of the connecting loop portion 12 is curved to form a loop. Suitable offsets have been formed in the body section to insure that the axes of the loops will be parallel and spaced from each other by the pitch distance of the belt. The principal characteristic of the new link is that the connecting loop has been closed in a generally downward direction while the cartridge gripping loops have been closed in a generally upward direction, or vice versa, the cross section of the new link approximating a closed S rather than the closed W of the conventional link discussed above. From the plan views of a belt assembled from the new links, Figs. 6 and 7, it will be seen that regardless of the direction in which the belt may be fed or whether single or double loop leading, the feeding and holding pawls will have symmetrical engagement with the belt and allow for a greater amount of stretching without causing feed stoppages. However, in order to eliminate stretching of the connecting loop and thus further increase the lifting capacity of the belt, a tongue 13 has been provided on the end of the connecting loop 12 which may be interlocked with the body portion 9 of the link or otherwise secured thereto. As the double loops are required to exert a resilient gripping action on the cartridge body it is not considered practicable to interlock them and positively prevent stretching in these parts. However, as the load is divided approximately equally between the double loops of a link, the tendency to stretch at this point is not severe and the load which may be sustained thereby generally exceeds the belt lifting capacity of the gun.

From an inspection of the blank shown in Fig. 5 it will be noted that the edge 14 of the body portion 9 opposed to the cartridge gripping member 11 diverges from the connecting loop forming portion 12 at an angle greater than a right angle and that the terminal end 15 of the member 11 is substantially parallel thereto. This construction insures that when the cartridge body gripping loop 11 has been closed upon itself the dividing line between the edges 14 and 15 will make a substantial angle with the plane including the axes of the loops, thus minimizing the chances for a feed or holding pawl to foul on that edge. It should be understood, however, that this is not always necessary and that my invention is deemed to include a link formed with that dividing line substantially parallel to the axes of the loops, in which case the angle between the edge 14 and the portion 12 of the blank will be substantially a right angle and the edge 15 will be substantially parallel thereto.

It will be noted that in the new link there are no severely reversed bends such as those found at the center tip of the W of the old link. Apart from the considerations already discussed the new link will therefore be stronger as tension in the

belt produces tension in the link body rather than a bending moment tending to straighten the link at the point of the W section. Elimination of the sharp bends also reduces the strains due to the cold working undergone in the dies during the forming operations and hence makes the manufacture of the new link faster and more economical than that of the old link. Another feature of economy of the new link is found in the metal saving which results from the use of the body portion of the link as an element in the wall of the cartridge gripping loops as well as in the connecting loop.

A further advantage of the use of the new belt will be that it will permit ammunition to be fed directly from standard containers to either right or left hand feed guns without the necessity of repacking to always present the belt to the gun double loop end first.

While it is contemplated that the new belt link will generally be made of metal it is not intended to be limited thereby, the invention being deemed to include a belt link of the configuration described herein formed of a plastic or other synthetic material.

In the specification the links have been described by reference to the direction in which the loops are formed. It should be noted that the directions referred to in the discussion of the forming of the link are vertical directions with regard to a lateral plane intersecting the body portion of the link and including the axes of the finished loops.

I claim:

1. A cartridge belt link comprising a body section having spaced apart wall portions, each having a free edge, spaced coaxial cartridge-gripping loops respectively integral with said wall portions and each curving as an extension from a respective wall portion of the body section opposite said free edge thereof into a circle terminating at the respective free edge thereof, at least one of said free edges and the terminal portion of its associated loop being inclined to the axis of the loop so that the junction of said terminal portion and said free edge is on a line diagonal to the axis of the loop, and a connecting loop axially parallel to the first named loops and integral with the body section.

2. A cartridge belt link comprising a body section having spaced apart wall portions, each having a free edge, spaced coaxial cartridge-gripping loops respectively integral with said wall portions and each curving as an extension from a respective wall portion of the body section opposite said free edge thereof into a circle terminating at the respective free edge thereof, said free edge and the terminal portion of each of said loops being inclined to the axis of the loop so that the junction of each of said terminal portions with its associated free edge is on a line diagonal to the axis of the loop, and a connecting loop axially parallel to the first named loops and integral with the body section.

3. A cartridge belt link comprising an intermediate body portion and a pair of spaced coaxial cartridge-engaging loops at one side of the body portion and a single cartridge-engaging loop at the other side of the body portion, said body portion including a transverse central wall section generally perpendicular to a horizontal plane passed through the axes of the loops, said central wall section having at each of its transversely opposite ends an integral end-wall section offset laterally toward the axis of the pair of loops,

each end-wall section being generally perpendicular to the horizontal plane passed through the axes of the loops, the pair of loops being respectively integral with the bottom portions of the end-wall sections and curving away therefrom into circles terminating respectively at the top portions of the end-wall sections, and the single loop being integral with the top portion

5 of the central wall section and curving away therefrom into a circle terminating at the bottom portion of said central wall section, the junction of each of the pair of loops with the top portion of its respective end-wall section being substantially on a line diagonal to the axis of said loops.
